SHOE OR SIMILAR ARTICLE

Jacob Sandler, Boston, Mass.

Application March 20, 1952, Serial No. 18,973

Term of patent 14 years

(Cl. D7—7)

To all whom it may concern:

Be it known that I, Jacob Sandler, a citizen of the United States of America, residing in Boston, county of Suffolk, and State of Massachusetts, have invented a new, original, and ornamental Design for a Shoe or Similar Article, of which the following is a specification, reference being had to the accompanying drawing, forming part thereof.

Fig. 1 is a side perspective view of a shoe, showing the essential features of my new design in full lines, the opposite side presenting substantially the same appearance as the side shown;

Fig. 2 is a fragmentary plan view of the vamp portion of the shoe illustrated in Fig. 1 for the purpose of illustrating more clearly the substantially round moccasin insert on the vamp of the shoe.

I claim:

The ornamental design for a shoe or similar article, substantially as shown and described.

JACOB SANDLER.
